UNITED STATES PATENT OFFICE.

ERNEST CLEFF, OF NEW YORK, N. Y., ASSIGNOR TO THE SPRINGFIELD METALLIC CASKET COMPANY, OF SPRINGFIELD, OHIO, A CORPORATION OF OHIO.

DESIGN FOR A NAME AND HANDLE PLATE FOR CASKETS.

No. 38,301.

Specification for Design.

Patented Oct. 30, 1906.

Application filed July 9, 1906. Serial No. 325,417. Term of patent 7 years.

To all whom it may concern:

Be it known that I, ERNEST CLEFF, a citizen of the United States, residing at New York, in the county of New York and State of New York, have invented a new, original, and ornamental Design for Name and Handle Plates for Caskets, of which the following is a specification.

My invention relates to a new, original, and ornamental design for name and handle plates for caskets.

The accompanying drawing is a plan view of such a plate embodying my design. The dotted lines indicate where the handle would be attached.

I claim—

The ornamental design for a name and handle plate for caskets as shown.

ERNEST CLEFF.
